UNITED STATES PATENT OFFICE.

FRED M. KIMBALL, OF SAN FRANCISCO, CALIFORNIA.

LIGHT PROJECTOR.

Application filed August 20, 1923. Serial No. 658,304.

To all whom it may concern:

Be it known that I, FRED M. KIMBALL, a citizen of the United States, residing at San Francisco, in the county of San Francisco and State of California, have invented certain new and useful Improvements in Light Projectors, of which the following is a specification.

My invention is an improved light projector, particularly applicable to automotive vehicles.

The object of my invention is to provide a projector in which there are no upwardly directed rays to confuse and dazzle an approaching driver.

My light projector is the combination of two reflectors mounted in a casing, with a lens in the front part of the casing. The rear of the casing contains a completely dome shaped reflector, which preferably has a peripheral flange secured to an inwardly extending flange on the casing. In front of this reflector is mounted a completely concave shaped reflector in both vertical and horizontal sections. This reflector preferably has a flange on the upper portion of its periphery secured to the flange of the dome shaped reflector. A light bulb is mounted in the second reflector, and projects the light on the main dome shaped reflector and thence through the lens.

In the annexed drawing in which the preferred form of my invention is shown,

Figure 1 is a transverse sectional view of my projector.

Figure 2 is a sectional view taken on the line 2-2 of Figure 1.

Referring more particularly to the drawing, my projector comprises a casing 1 to the forward end of which is suitably secured a lens 2.

A projecting reflector 3 has a flange 4 formed thereupon, and a plurality of screws 5 extend through said flange into suitable ears 6 which extend inwardly from the casing 1. Thus the reflector is secured within the casing 1.

A reflector 7 is positioned within the casing 1 and in the upper part thereof. A flange 8 is formed on said reflector 7 and is suitably secured to the flange 6, thus holding the reflector 7 in position. The lower edge 9 of the reflector 7 extends to

about the center of the forward edge of the reflector 3. A light 10 is suitably mounted in the reflector 7, the rays of which are directed downwardly and rearwardly into the reflector 3, where they are projected forwardly upon the road.

The curvature of the reflector 7 is such that the rays from the light 10 will be projected upon the reflector 3 at suitable parts to prevent any upwardly directed rays from the reflector 3. That is, the strongest light will be thrown upon the lower part of the reflector 3 which causes it to be projected horizontally.

Wires 11 feed the light 10 which extend from a plug 12 at the rear of the casing 1, into which the battery wires are secured.

From the above construction it will be seen that I have an efficient and simply constructed reflector projector, in which the main reflector 3 is completely dome shaped, and has mounted in front thereof a completely concave reflector 7, both being mounted inside the casing 1.

Having described my invention, I claim:

1. A light projector comprising in combination a casing, a completely dome shaped projecting reflector mounted therein having a flange on its front edge, a second reflector in the casing concave in section having a flange on its upper periphery only secured to the flange of the projecting reflector and a lamp in the second reflector adapted to project rays of light on the projecting reflector.

2. A light projector comprising in combination a casing having a flange therein, a completely dome shaped projecting reflector having a flange on its front periphery secured to the flange of the casing, a second reflector in the casing concave in cross section having a flange on its upper periphery only secured to the flange of the projecting reflector, a lamp in the second reflector adapted to project rays of light on the projecting reflector and a lens secured in the casing in front of the reflectors.

In testimony whereof I affix my signature.

FRED M. KIMBALL.
